(57) **CLAIM**

The ornamental design for a wave circuit pattern, as shown and described.

DESCRIPTION

FIG. 1 is a perspective view of a first embodiment of a wave circuit pattern showing my new design;

FIG. 2 is a front elevation view thereof, the back elevation view being identical;

FIG. 3 is a side view thereof, the opposite side view is a mirror image;

FIG. 4 is a perspective view of a second embodiment of a wave circuit pattern showing my new design;

FIG. 5 is a front elevation view thereof, the back elevation view being identical;

FIG. 6 is a side view thereof, the opposite side view is a mirror image;

FIG. 7 is a perspective view of a third embodiment of a wave circuit pattern showing my new design;

FIG. 8 is a front elevation view thereof, the back elevation view being identical;

FIG. 9 is a side view thereof, the opposite side view is a mirror image;

FIG. 10 is a perspective view of a fourth embodiment of a wave circuit pattern showing my new design;

FIG. 11 is a front elevation view thereof, the back elevation view being identical; and,

FIG. 12 is a side view thereof, the opposite side view is a mirror image.

The broken lines in FIGS. 1,2,4,5,7,8,10 and 11 adjacent to the solid wave circuit pattern show a repeating pattern that forms no part of the claimed design. All other broken lines are directed to environmental structure and form no part of the claimed design.
